CLAIM

The ornamental design for a cabinet, as shown and described.

DESCRIPTION

In a preferred embodiment, the nature of this product is as a cabinet that encloses an engine-electrical generator set.

FIG. 1 is a right, top, front perspective view of a cabinet embodying my new design;

FIG. 2 is a front elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a rear elevational view thereof; and,

FIG. 8 is a right, top, front perspective view of an alternative embodiment of a cabinet, embodying my new design, which is in an open state.

The broken line representations of apertures, louvers, latches and interior components in the figures are for the purpose of illustration only, and form no part of the claimed design.

The broken line(s) which define the bounds of the claimed design form no part thereof.
